UNITED STATES PATENT OFFICE.

JOHN A. FREY, OF NEW YORK, N. Y., ASSIGNOR TO C. RIESSNER AND COMPANY, OF SAME PLACE.

DESIGN FOR A TOP FOR INCASED VESSELS.

SPECIFICATION forming part of Design No. 18,461, dated July 17, 1888.

Application filed May 19, 1888. Serial No. 274,401. Term of patent 14 years.

To all whom it may concern:

Be it known that I, JOHN A. FREY, of New York, in the county of New York and State of New York, have invented a new Design for a Cap for Incased Glass Vessels, of which the following is a specification.

This invention consists of a design for a top for incased glass vessels or cans.

The accompanying drawing shows the cap in perspective applied to a can.

The design consists of the flat top or body A, having a vertical or depending flange, a. I have shown it provided with a small horizontally-projecting flange, b, at the lower edge 15 of the vertical flange a; but this may be omitted, if desired. Upon the top A is a short filling-tube with a cap, c, both being formed with a screw-thread, as shown. On the top of the

flat surface A, near one side, is a projecting spout, B, at the base of which is a raised circular projection, e, and projecting from the center of this is a stem, d, as shown in the drawing.

What I claim is—

The herein-described design for a top for incased glass vessels, consisting of the top A, provided with the depending flange a and with the spout B, having the projection e at its base, with the stem d projecting therefrom, substantially as shown.

In witness whereof I hereunto set my hand in the presence of two witnesses.

JOHN A. FREY.
